UNITED STATES PATENT OFFICE.

WILLIAM McCALLUM, OF YONKERS, NEW YORK, ASSIGNOR TO THE BIGELOW CARPET COMPANY, OF CLINTON, MASSACHUSETTS.

DESIGN FOR A CARPET.

SPECIFICATION forming part of Design No. 14,305, dated September 18, 1883.

Application filed August 3, 1883. Term of patent 3½ years.

To all whom it may concern:

Be it known that I, WILLIAM McCALLUM, of Yonkers, in the county of Westchester and State of New York, have invented and produced a new and original Design for a Carpet, of which the following is a full description, in connection with the accompanying photograph, which represents a face view of my new design for a carpet.

10 This invention relates to a new configuration for the border of a carpet or analogous fabric.

15 The body of the carpet is divided into two prominent stripes, A and B. The upper stripe, A, contains an undulating band, *a*, and below the same a series of fanciful figures, *b*. The lower stripe, B, contains a row of conventional

leaves, *d*, and an upright column or post, *e*, which supports semi-arches *f*, which appear to extend into the stripe A, and which connect 20 at their ends with uprights *g*, of fanciful outline, that traverse the stripe B. At the sides of these uprights *g* are clusters of leaves *h* and rosettes *i*. The upper part of the stripe B, outside of the uprights *g*, is separated from 25 the stripe A by a fanciful border, *j*.

I claim—

The design for a carpet, the same consisting of the stripes A B and figures *a b d e f g h i j*.

WILLIAM McCALLUM.
